UNITED STATES PATENT OFFICE.

JOHN F. STAPLES, OF LYNN, MASSACHUSETTS, ASSIGNOR TO BOSTON MACHINE WORKS COMPANY, OF LYNN, MASSACHUSETTS. A CORPORATION OF MASSACHUSETTS.

SEAM-PRESSING MACHINE.

1,234,950.

Specification of Letters Patent. Patented July 31, 1917.

Application filed October 28, 1916. Serial No. 128,324.

To all whom it may concern:

Be it known that I, JOHN F. STAPLES, a citizen of the United States, residing at Lynn, county of Essex, State of Massachusetts, have invented an Improvement in 5 Seam-Pressing Machines, of which the following description, in connection with the accompanying drawing, is a specification, like characters on the drawing representing 10 like parts.

This invention relates to a machine for pressing seams and especially to machines for this purpose which are provided with means for opening the seam to be pressed 15 and also with a vertically-vibratable pressing element constructed to give the seam a plurality of hammer-like blows as the work is fed forward thereby to set the open seam.

The object of my invention is to provide a 20 machine of this type with a heated seam-setting element which acts on the seam as it is pressed by the pressing element and operates to give a permanent set to the raw edges of the seam which are turned over and folded 25 by the pressing element. In operating on some kinds of material a permanent set cannot be given to the material merely by the action of the vibratable presser element, but if the action of this element is augmented by 30 that of a heated seam-setting or ironing element, then the folded edges of the pressed seam will be given a permanent set.

In order to give an understanding of my invention, I have illustrated in the drawing 35 a selected embodiment thereof which will now be described, after which the novel features will be pointed out in the appended claims.

Figure 1 is a side view of a machine embodying my invention;

Fig. 2 is a section on the line 2—2, Fig. 1;

Fig. 3 is an end view of said machine;

Figs. 4 and 5 are fragmentary detail views showing the operation of the seam-pressing 45 element;

Fig. 6 shows the seam before it is pressed;

Fig. 7 shows the seam after it is pressed;

Fig. 8 is a section on the line 8—8, Fig. 4.

1 indicates the frame of the machine which 50 sustains a work-supporting roll 2 over which the work is fed and also sustains a driving shaft 3 from which the operative parts of the machine are driven. 4 indicates the seam-pressing element, it being mounted in 55 a carrier 5 which is connected at its upper

end to and is operated by an eccentric 6 on the driving shaft 3. This carrier is provided with the slot 7 in which is received a guiding block 8 that is pivotally mounted on the frame. As a result of this construction, 60 the pressing element 4 has not only a vertical reciprocating movement toward and from the work-supporting roll 2, but has also a lateral swinging movement in the direction of the feed. The machine is intend- 65

ed to act on and press a seam such as shown in Fig. 6 by which the edges of two pieces 9 and 10 are secured together, this being accomplished by first opening out and separating the edges 11 and 12 and then pressing 70

said edges down against the fabric into the position shown in Fig. 7. This separating of the two edges 11 and 12 is accomplished by a wedge-shaped seam-opening member 13 which is forced between the edges 11 and 12 75

as the work is fed forward and not only separates said edges, but folds them over onto the body of the material. This opening member has associated therewith two guides 14 (one situated on each side thereof) which 80 assist in this operation. Only one of these guides can be seen in Fig. 3 as the other guide is directly back thereof. 15 is a guiding fin associated with the work-supporting roll 2 and which follows along the crease 16 85

as the work is drawn over the feed roll, said guiding fin operating to hold the work in proper position as it is fed. The parts thus far described are or may be as usual in seam-pressing machines of this nature and 90 form no part of my present invention. It will be sufficient to say that as the seam to be pressed is drawn across the roll 2, the plow-shaped seam-opening element 13 acts on the edges 11 and 12 progressively to separate them and fold them over against the body of the fabric, and as the folded edges leave the element 13 they are acted upon by the vertically-movable seam-pressing element 95

4 which is intended to give the edges a permanent set and thus complete the pressing of the seam. This element 4 not only moves vertically to accomplish the seam-pressing operation, but when it is in contact with the work, it moves forwardly thereby feeding 100 the work.

While a machine such as above described does satisfactory work when operating on some materials, yet when operating on canvas, duck or other relatively-stiff material, 110

the hammer-like action of the pressing element 4 does not give the edges 11 and 12 a permanent set, and as a result said edges will gradually separate from the body of the fabric and tend to assume their original position shown in Fig. 6. By my present invention, I have provided a heated seam-setting element which is constructed to operate with an ironing action on the edges 11 and 12 of the seam after they have been pressed by the pressing element 4. This ironing action of the heated seam-setting element gives the folded edges 11 and 12 a permanent set even though the material is comparatively stiff and unyielding. This seam-setting element is shown at 17 and it is forked at its end so that it can straddle the pressing element 4. Means are provided for heating the seam-setting element 17 and also for giving it a vertical and horizontal movement, the horizontal movement occurring when the seam-setting element is in its depressed position in contact with the work and when the seam-setting element 4 is being raised, and consequently when the work is at rest. As a result, the horizontal movement of the seam-setting element produces an ironing effect on the work which serves to set the fold in the edges 11 and 12.

While any suitable means for heating the seam-setting element 17 may be employed and said element may be mounted in any convenient manner to produce the above results, the construction that I have herein shown has proved to be a practical one. In the construction shown the seam-setting element 17 is heated electrically, said element being formed on the lower end of a casing 18 adapted to receive an electrical heating unit 19 which is connected by wires 20 to the source of current supply. This casing 18 is shown as secured to but insulated from a bracket 21 which in turn is adjustably carried by the lower end of an actuating lever 22, the latter being provided with the vertical portion 23 provided with the slot 24 in which is received a guiding block 25 that is pivoted to the frame at 26. The upper end 50 of the lever 22 is formed with an eccentric strap 27 which embraces an eccentric 28 on the driving shaft 3. With this construction, the rotation of the shaft 3 will operate through the eccentric to give the lower end 55 of the portion 23 of the lever 22 both a vertical movement and a horizontal movement in the direction in which the work is fed. The horizontal movement in the direction of feed occurs while the seam-setting element is in its depressed position in contact with the work and at the time when the work is not being fed by the seam-setting and feeding element 4. Consequently, the horizontal movement of the seam-setting element 17 will give a sort of ironing action

which is effective in setting the seam. The cycle of operations is illustrated in Figs. 4 and 5. Fig. 4 shows the seam-setting element 4 depressed into contact with the seam and the ironing or seam-setting element 17 raised. While the seam-setting element 4 is thus depressed into contact with the work it is moved laterally or horizontally into the dotted line position shown in Fig. 4, thus giving the work a feeding movement, and during this time the seam-setting element 17 is moved horizontally in an opposite direction, as shown by dotted lines Fig. 4. The seam-setting element 4 is then raised into the position shown in Fig. 5, and the seam-setting element 17 is depressed into contact with the folded edges 11 and 12, as seen in full lines, Fig. 5. The seam-setting element 4 is then moved horizontally preparatory to its next downward movement, as shown by dotted lines, Fig. 5, and during this time, the seam-setting element 17 is moved horizontally while in contact with the work into the dotted line position shown in Fig. 5. During this latter movement of the seam-setting element the work will be stationary and the seam-setting element, thus has an ironing action which is effective in giving a permanent set to the folded edges 11 and 12. With my improvement it is possible to press the seam of almost any material in such a way that the folded edges of the seam will have a permanent set.

I have shown at 30 a pulling spring, one end of which is connected to the frame and the other end of which is connected to the bracket 21, this spring being for the purpose of assisting in giving the seam-setting element its raising movement.

I claim:

1. In a seam-setting machine, the combination with a work support, of a seam-setting element, means to give said element a seam-setting movement toward and from the work support and a horizontal feeding movement, and a heated seam-setting element to act on the pressed seam thereby to give the latter a permanent set.

2. In a seam-setting machine, the combination with a work support, of a seam-setting element, means to give said element a seam-setting movement toward and from the work support and a horizontal feeding movement, and an electrically-heated seam-setting element to act on the pressed seam thereby to give the latter a permanent set.

3. In a seam-setting machine, the combination with a work support, of a seam-setting element, means to give said element a seam-setting movement toward and from the work support and a horizontal feeding movement, a heated seam-setting element, and means to cause said seam-setting element to act on the pressed seam with an ironing movement.

4. In a seam-pressing machine, the combination with a work support, of a seam-pressing element, means to give said element a seam-pressing movement toward and from the work support and a horizontal feeding movement, a heated seam-setting element arranged to act on the folded edges of the seam, and means to cause said seam-setting element to act on said folded edges with an ironing movement.
5. In a seam-pressing machine, the combination with a work support, of a seam-pressing element, means to give said element a seam-pressing movement toward and from the work support and also a feeding movement intermittently, a heated seam-setting element, and means to cause the latter to have a rubbing or ironing action on the pressed seam between the feeding movements of the work.
6. In a seam-pressing machine, the combination with a work-support, of a seam-pressing element, means to actuate said element thereby to press the seam, and a heated seam-setting element to act on the pressed seam thereby to give the latter a permanent set.
7. In a seam-pressing machine, the combination with a work-support, of a seam-pressing element, means to actuate said element thereby to press the seam, a heated seam-setting element, and means to cause said seam-setting element to act on the pressed seam with an ironing movement.
8. In a seam-pressing machine, the combination with a work-support, of a seam-pressing element, means to actuate said element thereby to press a seam, a heated seam-setting element arranged to actuate the folded edges of the pressed seam, and means to cause said seam-setting element to act on said folded edges with an ironing movement.

In testimony whereof, I have signed my name to this specification.

JOHN F. STAPLES.
